(57) **CLAIM**

The ornamental design for a beverage capsule, as shown and described.

DESCRIPTION

FIG. 1 is a perspective view of a beverage pod showing the new design;

FIG. 2 is a left side view thereof;

FIG. 3 is a right side view thereof;

FIG. 4 is a front side view thereof;

FIG. 5 is a back side view thereof;

FIG. 6 is a top view thereof;

FIG. 7 is a bottom view thereof;

FIG. 8 is an enlarged view of area 8 in FIG. 1;

FIG. 9 is a cross-sectional view taken along line 9-9 in FIG. 6; and,

FIG. 10 is an enlarged view of area 10 in FIG. 9 thereof. The dot-dash broken lines in the figure drawings, designating the boundary of the enlarged view, form no part of the claimed design.

1 Claim, 10 Drawing Sheets
